Fig. 5

FIGURE 1 is a front elevational view of a hanger for garments, textiles or the like showing my new design;

FIGURES 2 and 3 are top and bottom plan views thereof, respectively;

FIGURES 5 and 6 are elevational views taken from the right and left ends thereof, respectively.

I claim:

The ornamental design for a hanger for garments, textiles or the like, substantially as shown.
